No. 732,742.

PATENTED JULY 7, 1903.

A. S. HELD.
COMBINED MOP AND SCRUB BRUSH.

APPLICATION FILED OCT. 10, 1902.

NO MODEL.

UNITED STATES PATENT OFFICE.

AUGUST S. HELD, OF FREEPORT, ILLINOIS.

COMBINED MOP AND SCRUB-BRUSH.

SPECIFICATION forming part of Letters Patent No. 732,742, dated July 7, 1903.

Application filed October 10, 1902. Serial No. 126,682. (No model.)

To all whom it may concern:

Be it known that I, AUGUST S. HELD, a citizen of the United States of America, residing at Freeport, in the county of Stephenson and 5 State of Illinois, have invented certain new and useful Improvements in a Combined Mop and Scrub-Brush, of which the following is a specification.

This invention has for its object the production of combined mops and scrub-brushes so contrived and arranged that they may be used both in such combination and separately; and it consists of certain new and useful features of construction and combinations of parts especially devised to those ends, all as herein-after fully described, and specifically pointed out in the claims.

Referring to the accompanying drawings, which form a part of this specification, Figure 1 is a top plan view of a combined mop and scrub-brush embodying my invention and adapted to be used both for mopping and scrubbing. Fig. 2 is a section at the dotted line 2 3 in Fig. 1 of parts there shown. Fig. 25 3 is a like section, also at such dotted line 2 3 in Fig. 1, showing the movable jaw of the mop-head thrown away from its fixed jaw by means of its controlling-lever in order that the brush-attaching plate thereof, with 30 its brush, may be detached therefrom. Fig. 4 is an isometrical detail of the brush-attaching plate.

Like letters of reference indicate corresponding parts throughout the several views.

35 A is a mop-handle.

B' represents a casting composing the fixed clamping-jaw of the mop-head and its handle-socket.

C is a counterpart movable clamping-jaw 40 parallel with the fixed jaw B, having its ends C' extending and converging rearwardly and united by connecting means, to be described hereinafter.

D is a ring encircling and slidable on the 45 handle A.

E is a bifurcated lever mounted by the free ends E of its furcations on the pivot-bearings E' on the ring D, and having openings E' therethrough to admit and pivotally connect 50 with the ends C' of the movable jaw C.

F is a coiled spring encircling the handle

A, compressible between the fixed clamping-jaw B and slidable ring D and normally acting to force the movable jaw C toward the fixed jaw B.

55

G is a mop inserted between the jaws B and C.

H is a brush-attaching plate, having one edge portion H' thereof bent in trough-like form, preferably substantially U-shaped in cross-section, to adapt it to admit thereinto the movable jaw C and portion G' of the mop G looped thereover and provided with transversely-projecting lugs H² bestriding the central portion of the fixed jaw B to prevent the plate H from tilting.

I is a scrub-brush secured by means of screws I to the brush-attaching plate H.

Figs. 1 to 3, inclusive, represent the utensil usable both as a scrub-brush and as a mop. 70 Obviously if the movable jaw C be released by swinging the free end of the lever E away from the handle A, as in Fig. 3, the brush may be detached therefrom and both brush and mop will become available for use separately.

What I claim as new, and desire to secure by Letters Patent, is—

1. In a utensil of the class described, in combination, a handle with a fixed clamping-jaw fast thereto, a movable clamping-jaw—parallel with the fixed jaw—having its ends extending and converging rearwardly and united by connecting means, releasable means for clamping the movable jaw against the fixed jaw, a mop inserted between the jaws and looped over the movable jaw, a brush-attaching plate having one edge portion thereof bent in trough-like form—preferably substantially U-shaped in cross-section—to adapt it to admit thereinto the movable jaw and portion of the mop looped thereover, and a scrub-brush secured to the brush-attaching plate, substantially as and for the purpose specified.

95

2. In a utensil of the class described, in combination, a handle with a fixed clamping-jaw fast thereto, a movable clamping-jaw—parallel with the fixed jaw—having its ends extending and converging rearwardly and united by connecting means, releasable means for clamping the movable jaw against

100

the fixed jaw, a mop inserted between the jaws and looped over the movable jaw, a brush-attaching plate having one edge portion thereof bent in trough-like form—preferably substantially U-shaped in cross-section—to adapt it to admit thereinto the movable jaw and portion of the mop looped thereover and provided with transversely-projecting lugs bestriding the central portion of the fixed jaw, and a scrub-brush secured to the

brush-attaching plate, substantially as and for the purpose specified.

In testimony whereof I have signed my name to this specification in the presence of two subscribing witnesses:

AUGUST S. HELD.

Witnesses:

JOHN M. IRWIN,
W. H. J. STRATTON.
